US00D826871S

(12) **United States Design Patent** (10) **Patent No.:** **US D826,871 S**
Reiherzer et al. (45) **Date of Patent:** **** Aug. 28, 2018**

(54) **LIGHT EMITTING DIODE DEVICE**(71) Applicant: **CREE, INC.**, Durham, NC (US)(72) Inventors: **Jesse Reiherzer**, Wake Forest, NC (US); **Jeremy Nevins**, Cary, NC (US); **Joseph Clark**, Raleigh, NC (US)(73) Assignee: **CREE, INC.**, Durham, NC (US)(***) Term: **14 Years**(21) Appl. No.: **29/511,587**(22) Filed: **Dec. 11, 2014**(51) LOC (11) Cl. **13-03**

(52) U.S. Cl.

(57) **CLAIM**

The ornamental design for light emitting diode device, as shown and described herein.

DESCRIPTION

FIG. 1 is a bottom perspective view of a light emitting diode device according to an embodiment of the present invention. FIG. 2 is a top view of the light emitting diode device shown in FIG. 1.

FIG. 3 is a bottom view of the light emitting diode device shown in FIG. 1.

FIG. 4 is a front elevation view of the light emitting diode device shown in FIG. 1.

FIG. 5 is a right side elevation view of the light emitting diode device shown in FIG. 1.

FIG. 6 is a back elevation view of the light emitting diode device shown in FIG. 1.

FIG. 7 is a left side elevation view of the light emitting diode device shown in FIG. 1.

FIG. 8 is a bottom perspective view of a light emitting diode device according to an embodiment of the present invention.

FIG. 9 is a top view of the light emitting diode device shown in FIG. 8.

FIG. 10 is a bottom view of the light emitting diode device shown in FIG. 8.

FIG. 11 is a front elevation view of the light emitting diode device shown in FIG. 8.

FIG. 12 is a right side elevation view of the light emitting diode device shown in FIG. 8.

FIG. 13 is a back elevation view of the light emitting diode device shown in FIG. 8.

FIG. 14 is a left side elevation view of the light emitting diode device shown in FIG. 8.

FIG. 15 is a bottom perspective view of a light emitting diode device according to an embodiment of the present invention.

FIG. 16 is a top view of the light emitting diode device shown in FIG. 15.

FIG. 17 is a bottom view of the light emitting diode device shown in FIG. 15.

FIG. 18 is a front elevation view of the light emitting diode device shown in FIG. 15.

FIG. 19 is a right side elevation view of the light emitting diode device shown in FIG. 15.

FIG. 20 is a back elevation view of the light emitting diode device shown in FIG. 15.

FIG. 21 is a left side elevation view of the light emitting diode device shown in FIG. 15.

FIG. 22 is a bottom perspective view of a light emitting diode device according to an embodiment of the present invention.

FIG. 23 is a top view of the light emitting diode device shown in FIG. 22.

FIG. 24 is a bottom view of the light emitting diode device shown in FIG. 22.

FIG. 25 is a front elevation view of the light emitting diode device shown in FIG. 22.

FIG. 26 is a right side elevation view of the light emitting diode device shown in FIG. 22.

FIG. 27 is a back elevation view of the light emitting diode device shown in FIG. 22.

FIG. 28 is a left side elevation view of the light emitting diode device shown in FIG. 22.

FIG. 29 is a bottom perspective view of a light emitting diode device according to an embodiment of the present invention.

FIG. 30 is a top view of the light emitting diode device shown in FIG. 29.

FIG. 31 is a bottom view of the light emitting diode device shown in FIG. 29.

FIG. 32 is a front elevation view of the light emitting diode device shown in FIG. 29.

FIG. 33 is a right side elevation view of the light emitting diode device shown in FIG. 29.

FIG. 34 is a back elevation view of the light emitting diode device shown in FIG. 29.

FIG. 35 is a left side elevation view of the light emitting diode device shown in FIG. 29.

FIG. 36 is a bottom perspective view of a light emitting diode device according to an embodiment of the present invention.

FIG. 37 is a top view of the light emitting diode device shown in FIG. 36.

FIG. 38 is a bottom view of the light emitting diode device shown in FIG. 36.

FIG. 39 is a front elevation view of the light emitting diode device shown in FIG. 36.

FIG. 40 is a right side elevation view of the light emitting diode device shown in FIG. 36.

FIG. 41 is a back elevation view of the light emitting diode device shown in FIG. 36; and,

FIG. 42 is a left side elevation view of the light emitting diode device shown in FIG. 36.

The broken lines of FIGS. 1-42 illustrate portions of the various embodiments of the light emitting diode device which form no part of the claimed design.
